H. Cassell,
Washing Machine,
No 19,911. Patented Apr. 13, 1858.

UNITED STATES PATENT OFFICE.

HENRY CASSELL, OF FREDERICKTOWN, OHIO.

WASHING-MACHINE.

Specification of Letters Patent No. 19,911, dated April 13, 1858.

To all whom it may concern:

Be it known that I, HENRY CASSELL, of Fredericktown, in the county of Knox and State of Ohio, have invented a new and Improved Washing-Machine; and I do hereby declare that the following is a full, clear, and exact description of the same, reference being had to the annexed drawings, making a part of this specification, in which—

10 Figure 1, is a side view of my improvement, the tub being bisected vertically through its center. Fig. 2, is a transverse vertical section of do, (x), (x) Fig. 1, showing the plane of section. Fig. 3, is a section 15 of a portion of the driving shaft of the machine.

Similar letters of reference indicate corresponding parts in the several figures.

The nature of my improvement consists in 20 the arrangement of mechanism employed for operating the pounders attached to the machine for the purpose of drawing them up sufficiently high so that they may be forced against the clothing being washed 25 sufficiently hard to do good execution in the washing process and at the same time—by which arrangement I obtain a compact machine in its parts for the purposes of operating the pounders.

30 To enable those skilled in the art to make and use my invention, I will proceed to describe its construction and operation.

A, represents a platform or bed on which a tub B, is placed, said tub having a spindle 35 or arbor C, passing vertically through its center, the lower end of the spindle being fitted on a center pivot (a), in the platform or bed A, and the upper end fitted in a bearing (b), attached to a cross piece (c), the 40 ends of which are attached to uprights (d), (d), to which the platform or bed A, is attached. The tub consequently is allowed to rotate freely, and the upper edge of the tub has teeth (e), formed on it in which a pinion 45 (f), gears. The axis of this pinion is fitted in the lower end of a vertical sliding bar D, which is placed against the inner side of one of the uprights (d), and has a lever E, attached to it, the outer end of said lever 50 being attached or pivoted to said upright (d). The axis of the pinion (f), has a pulley (g), upon it, around which pulley a belt (h), passes, and this belt passes around a pulley (i), on a driving shaft F, the axis or 55 journals of which are fitted in the uprights

(d), (d). To one end of the shaft F, or crank G, is attached.

H, represents the cover of the tub. This cover is attached to the lower end of a vertical frame I, which is fitted between guides 60 (j), (j), attached to cross pieces (k), (k), which are secured to the uprights (d), (d). The cover is sustained at the upper part of the tub by a pawl or catch (l), shown in Fig. 1. The cover is jointed or has flaps 65 (m), connected to a center part (n), by hinges (o), see Fig. 2, the frame I, being attached to the part (n).

J, J, are two vertical pounders, the lower ends of which pass through the center part 70 (n), of the cover H. The upper ends of the pounders pass through a cross piece K, which is fitted on tenons (p), on the upper ends of the uprights (d), (d). The cross piece may be raised or lowered on the tenons 75 (p), and secured at the desired point by pins (g). The upper parts of the pounders have spiral springs (r), upon them, said spring bearing against the cross piece K, and shoulders (s), on the pounders.

To each pounder J, there is attached a strap (t), having a metal hook (u), at its end. These hooks are fitted in grooves or recesses (v), made circumferentially in the shaft F, see Figs. 2 and 3. To the shaft F, 85 there are attached four spring catches or pawls (w), two of which are shown in Fig. 3. The catches or pawls are fitted in grooves in the shaft F. To a cross piece L, which is attached to the uprights (d), (d), there is secured a spring M. This spring projects over the catches or pawls (w), as shown clearly in Fig. 2.

The operation is as follows: The clothes are placed in the tub B, and a requisite 95 quantity of soap and water is placed therein. The pinion (f), is thrown in gear with the teeth on the upper edge of the tub B. By turning the shaft F, the tub is rotated, the belt (h), rotating the pinion (f). As the 100 shaft F, rotates the catches or pawls (w), act against the hooks (u), and draw upward or raise the pounders J, J, and as the catches or pawls pass underneath the upper part of the spring M, they are depressed in their 105 grooves and the hooks (u), are liberated, the pounders being then forced down upon the clothes within the tub B, by the springs (r). The two pounders are operated or raised and lowered alternately, and as the 110

tub rotates the clothes are passed underneath the pounders so that the whole amount of clothes within the tub will be sufficiently acted upon by the pounders.

- 5 The above invention has been practically tested and operates rapidly and well.

Having thus described my invention what I claim as my improvement and desire to secure by Letters Patent is—

- 0 The arrangement of the spring pawls (w)

and grooves (b) on the shaft (F) and these arranged with the hooks (u) for elevating the pounders, and the spring (M) for purposes mentioned in the foregoing specification.

HENRY CASSELL.
